MOTOR FUEL

Weldon G. Annable, Mundelein, and Robert M. Haines, Crystal Lake, Ill., assignors to The Pure Oil Company, Chicago, Ill., a corporation of Ohio

No Drawing. Application November 13, 1956
Serial No. 621,512

12 Claims. (Cl. 44—66)

This invention relates to motor fuels and particularly motor fuels for use in spark-ignited, internal combustion engines. The invention is more particularly concerned with motor fuels containing a small amount of additive to mitigate the formation of deposits in the induction systems of automotive engines and to the method for inhibiting formation of such deposits.

Motor fuels containing tetraethyl lead have a tendency to deposit solid material in the induction system, that is, the area between the carburetor and combustion chamber of internal combustion engines, which interferes with the efficient operation of the engine. We have discovered that induction system deposits can be greatly mitigated by adding to the motor fuel or gasoline small amounts of certain types of additives.

An object of the invention is to provide an additive which when added to leaded motor fuel will lessen the tendency of the motor fuel to form deposits in the induction systems of internal combustion engines.

Another object of the invention is to provide a leaded motor fuel which will not form deposits or which forms only small amounts of deposits in the induction system of an automotive engine of the internal combustion type.

A further object of the invention is to provide a method for mitigating deposition in the induction system of internal combustion engines.

Other objects of the invention will make themselves manifest from the following detailed description of the invention.

We have discovered that partially esterified alkyl and alkylaryl glycosides when added to leaded motor fuel greatly mitigate the tendency of such fuels to form deposits in the induction system of spark ignition type internal combustion engines. These deposits tend to form in the area between the carburetor and the combustion chamber of the engine, particularly in the intake manifold and on the valves, causing constriction of the intake manifold and preventing proper closing of the valves, with resultant burning thereof. This tendency to form deposits is aggravated in connection with the use of modern fuels containing in addition to saturated hydrocarbons, unsaturated and aromatic hydrocarbons and tetraethyl lead.

We have found that by adding to such motor fuels glycoside esters of the type hereinbefore described in an amount between about 0.005 and 5% by weight, induction system deposits can be eliminated or greatly reduced. We have found that the additive in the amount of about 0.01% by weight is effective for this purpose. This corresponds to about 35 pounds of glycoside ester per 1000 barrels of gasoline or similar motor fuel.

2

The glycosides useful in preparing the esters of our invention are represented by the formula

in which R is an alkyl or alkylaryl radical containing 1 to 12 carbon atoms and x is an integer of 1-8. These glycosides are esterified with 1 to 4 molecules of a mono-carboxylic acid, such as fatty acids, aromatic acids and 10 naphthenic acids, containing 8 to 24 carbon atoms per molecule. Mono, di, tri and tetraesters of the glycosides are useful. However, the effectiveness of the additive in reducing deposit formation is dependent on the chain length of the esterifying acid and on the number of acid 15 groups in the molecule. Shorter chains and less complete esterification produce esters which are more effective than those in which acids of longer chain lengths are used or more acid groups are attached to the glycoside by esterification. However, since it is necessary to make 20 the glycoside soluble in the gasoline in the amount in which it is added, a sufficient number of acidic groups or acidic groups of long enough chain length must be attached to the glycoside to make it soluble. The following 25 groups of compounds and specific examples under each group are useful as additives for the purpose of our invention:

I. Hexoside mono esters

30

35

40 in which R is an alkyl or alkylaryl radical containing 1-12 carbon atoms and R' is an aliphatic chain containing 7-23 carbon atoms.

Specific examples of compounds in this group are the mono-caprylate of methyl hexoside, mono-caprylate of lauryl hexoside, mono-caprylate of ethyl phenyl hexoside and the monocaprylate of propyl, butyl, amyl, hexyl, octyl, nonyl, decyl, and hexyl phenyl hexoside. Further examples are the mono-laurate, mono-palmitate, mono-stearate and mono-linoleate of the foregoing hexosides.

II. Di, tri and tetra esters of alkyl and alkylaryl hexosides

55

60

65

in which R is an alkyl or alkylaryl radical having 1-12 carbon atoms, R₁ is an aliphatic chain containing 7-23 carbon atoms, and R₂ is either hydrogen or a C₈-C₂₄ fatty acid minus OH from the carboxyl group.

Specific examples falling within this group are the di, tri and tetra-laurates of methyl hexoside and the di, tri and tetralaurate of all the hexosides listed under I.

III. Tetroside esters

in which R, R₁ and R₂ are defined the same as in II.

As a specific example where R is (CH₃), R₁ is C₁₃H₁₇, and R₂ is hydrogen, the compound is the monooleate of methyl tetroside. It will be apparent that any of the R groups under I can be substituted for R in Formula III and any fatty acid given under I can be substituted for oleic acid to give a corresponding tetroside ester.

IV. Pentoside esters

in which R, R₁ and R₂ are defined the same as in II.

Specific examples are trioleate of methyl pentoside and the mono and diesters of palmitic, stearic and linoleic acids in which the R group can be ethyl, ethyl phenyl or any of the specific alkyl or alkylaryl groups mentioned under II.

V. Other examples are the octoside esters such as the monooleate ester of ethyl octoside, and decoside esters such as the monooleate of ethyl decoside. As in the previous groups, the esters may contain one to four acid radicals and various alkyl and alkylaryl radicals can be substituted for the ethyl radical.

In order to demonstrate the invention, gasoline made by fluid catalytic cracking of petroleum oil was mixed with 25 pounds of each of the glycoside esters listed in the following table, per 1000 barrels of gasoline. The gasoline used in these tests had the following characteristics:

Reed vapor pressure..... 8.2 p. s. i.
ASTM:

I. B. P.....	104° F.
5.....	122° F.
10.....	132° F.
20.....	148° F.
30.....	168° F.
40.....	192° F.
50.....	224° F.
60.....	260° F.
70.....	295° F.
80.....	331° F.
90.....	372° F.
95.....	399° F.
E. P.....	412° F.

Additives:

Antioxidant.....	10 lb./1000 bbl.
Metal deactivator.....	0.25 lb./1000 bbl.
Tetraethyl lead.....	3 cc./gal.

Each test run was conducted in a one-cylinder Lawson engine and the run lasted for a period of 12 hours.

Table I

Run No.	Additive	Percent Reduction in Deposits
A.....	none.....	(0.0894 gram)
B.....	methyl glucoside trilauroate.....	78
C.....	methyl glucoside tetralaurate.....	52
D.....	methyl glucoside trioleate.....	49
E.....	methyl glucoside tetraoleate.....	39

Run A was made on the motor fuel without any glucoside ester added thereto to determine the magnitude of the deposit as a basis of comparison for the subsequent runs made with addition of the glucoside esters. Run B, in which the methyl glucoside trilauroate was used, produced the largest reduction in deposits. By comparing runs B, C, D and E, it will be seen that the glucoside which contained the shortest acid chain (lauroate) and the glucoside which contained the fewest number of acid groups (trilauroate) gave the largest reduction in deposits. Similarly, the ester containing the longest and greatest number of acid groups (tetraoleate) gave the lowest reduction in deposits. All of the glucoside esters tested, however, gave a significant reduction in induction system deposits.

It will be apparent that to get the same effectiveness in deposit reduction it is necessary to use a larger amount of glycoside ester when the acid radical is longer or more acid groups are attached to the glycoside than in the case where the acid radical is shorter or contains a lesser number of acid groups. The glycoside appears to be the active constituent of the ester in reducing deposits. The esterifying acid merely serves to solubilize the glycoside in the motor fuel.

Although in the specific examples fatty acids are used to esterify the glycoside, it will be understood that other acids, such as the aromatic and naphthenic acids having a sufficient number of carbon atoms to solubilize the resulting ester, can be used, such as toluic acid, cinnamic acid, phenyl propionic acid, and 2,2,6-trimethylcyclohexanecarboxylic acid.

We claim as our invention:

1. A hydrocarbon motor fuel of the gasoline boiling range containing about 0.005 to 5.0 wt. % of esterified glycoside, said glycoside corresponding to the formula

in which x is 1-8, R is from the group consisting of alkyl and alkylaryl radicals containing 1 to 12 carbon atoms, and the glycoside is esterified with one to four molecules of a monobasic aliphatic acid containing from 8 to 24 carbon atoms per molecule.

2. A motor fuel in accordance with claim 1 in which R is an alkyl group.

3. A motor fuel in accordance with claim 1 in which R is an alkylaryl group.

4. A motor fuel in accordance with claim 1 in which the esterified glucoside is a monoester of a fatty acid.

5. A motor fuel in accordance with claim 1 in which the ester is a triester present in the amount of about .005 to 5% by weight.

6. A motor fuel in accordance with claim 1 in which the ester is a tetraester.

7. A motor fuel in accordance with claim 4 in which the esterified glucoside is the monocaprylate.

8. A motor fuel in accordance with claim 4 in which the ester is the monocaprylate of lauryl hexoside.

9. A motor fuel in accordance with claim 5 in which the ester is the trilauroate ester of methyl glucoside present in the amount of about .01%.

10. A motor fuel in accordance with claim 5 in which

the ester is the trioleate of methyl glucoside present in the amount of about .01% by weight.

11. A motor fuel in accordance with claim 6 in which the ester is the tetralaurate of methyl glucoside present in the amount of .01% by weight.

12. A motor fuel in accordance with claim 6 in which the ester is the tetraoleate of methyl glucoside present in the amount of .01% by weight.
